UNITED STATES PATENT OFFICE.

HENRY RIUS AND JOSEPH MARIA FONTANALS, OF NEW YORK, N. Y.

PURSE.

Application filed November 29, 1921. Serial No. 518,588.

To all whom it may concern:

Be it known that we, HENRY RIUS, a citizen of the United States, and JOSEPH M. FONTANALS, a citizen of the United States, 5 and residents of the city of New York, borough of Manhattan, in the county and State of New York, have invented new and useful Improvements in Purses, of which the following is a full, clear, and exact description.

10 This invention relates to improvements in purses.

The general object of the invention is the provision of a novelty purse, sewing bag or the like, having means provided in conjunction with the bag and carrying means for giving the whole the appearance of a dressed doll.

15 A further object of the invention is the provision of means for so associating the decorative means with the bag that the former may be easily removed, so that access to the bag may be had.

20 These and other objects of the invention will be more clearly understood from the following detailed description and accompanying drawings.

25 Figure 2 is a side elevation with a portion of the doll bust and dress cut away to show the purse and the means of associating the doll bust with the draw strings;

30 Figure 4 is a side elevation of the modification with a portion of the doll bust and dress cut away to show how the doll bust and dress are associated.

35 Referring to the above-mentioned drawings, a bag 10 is shown provided with draw strings 11. Attached to the upper portion of the bag and extending downward enclosing the same is a skirt 12. The draw strings 11 extend through an opening 13 provided in the doll bust 14. The opening is sufficiently large so that the doll bust may be easily slid up and down upon the draw strings. Carried by the doll bust is the upper portion of a dress 15, which is made 40 from the same material as the skirt 12, and so arranged that it may be associated with the skirt so that the whole will give the appearance of a complete dress. Positioned on the head of the doll bust is a decorative 45 hat 16. The doll bust 14 may be made of a variety of shapes and decorated in various manners so as to create pleasing effects to appeal to the tastes of different individuals.

One modification of the improved purse, sewing bag or the like, is shown in Figures 60 3 and 4. In this construction the skirt 12 is attached to the upper portion of the dress 15 suspended from the doll bust 14 so as to completely cover the bag 10. Instead of the decorative hat 16, provided in the preferred form shown in Figures 1 and 2, hair 65 17 which serves as a decorative means is attached to the head of the doll bust.

This improved purse is carried by means of the draw strings 11 which also serve to 70 close the bag 10. In order to gain access to the bag the doll bust 14 is taken hold of and the bag 10 drawn down from underneath the skirt, drawing the drawstrings 11 through the opening 13 in the doll bust 14. Then the 75 bag 10 is opened like any other bag closed by means of draw strings.

We would state in conclusion that while the illustrated examples constitute practical embodiments of our invention we do not 80 limit ourselves strictly to the exact details herein illustrated since manifestly the same can be considerably varied without departing from the spirit of the invention as defined in the appended claims.

Claims.

1. As a new article of manufacture, a 85 purse of the class described comprising a bag having draw strings in conjunction therewith for closing it, a doll bust slidably mounted on the draw strings so that it will seat on the bag, and means associated with the bag and purse to give the whole the appearance of a dressed doll.

2. As a new article of manufacture, a 90 purse or sewing bag of the class described comprising a bag having draw strings in conjunction therewith for closing, a doll bust slidably mounted on the draw strings 95 so that it will seat on the bag, a decorative hat positioned on the head of the doll bust, and a dress, having a skirt, which overlies the bag to give the whole the appearance of a dressed doll, carried by the doll bust.

3. As a new article of manufacture, a 100 purse or sewing bag of the class described comprising a bag having draw strings in conjunction therewith for controlling the opening and closing, a doll bust slidably 105 mounted on the draw strings so that it will seat on the bag, a decorative hat positioned on the head of the doll bust, and a dress having a skirt which slides over the bag to cover it so as to give the whole the appearance of a dressed doll.

5. As a new article of manufacture, a purse of the class described, comprising a bag, means for controlling the opening and closing of the bag, means for carrying the bag, a doll bust associated with the carrying means, a decorative hat positioned on the head of the doll bust, and a dress carried by the doll bust so that it may be associated with the bag to give the whole the appearance of a dressed doll.

10 5. As a new article of manufacture, a carrying container of the class described comprising a bag having draw strings in conjunction therewith for controlling the opening and closing of them, a doll bust having an opening extending vertically there-through mounted on the draw strings so that it will seat on the bag, a decorative hat positioned on the doll bust head, and a dress carried by the doll bust and having the skirt associated with the bag to give the whole the 15 20 25 appearance of a dressed doll.
